United States Patent

Des. 238,364

Patented Jan. 6, 1976

238,364

COMBINED HEATER AND FIREPLACE

Nick S. Kategianis, Park Ridge, Ill., assignor to
Autocrat Corporation, New Athens, Ill.

Filed Mar. 10, 1975, Ser. No. 556,547

Term of patent 14 years

Int. Cl. D23—03

U.S. Cl. D23—93

FIG. 1

FIG. 2

FIG. 3

FIG. 4

FIG. 5

FIG. 1 is a front elevational view of a combined heater and fireplace showing my new design.

FIG. 2 is a top plan view thereof.

FIG. 3 is a side elevational view taken on the right-hand side of FIG. 1.

FIG. 4 is a side elevational view taken on the left-hand side of FIG. 1.

FIG. 5 is a rear elevational view thereof.

I claim:

The ornamental design for a combined heater and fireplace, as shown.
